UNITED STATES PATENT OFFICE.

JEAN MARIE GLOPPE, OF LYON, FRANCE.

DESK.

1,347,025.

Specification of Letters Patent.

Patented July 20, 1920.

Application filed January 23, 1920. Serial No. 353,410.

To all whom it may concern:

Be it known that I, JEAN MARIE GLOPPE, manufacturer, and a citizen of the French Republic, of Lyon, France, have invented 5 certain new and useful Improvements in Desks, of which the following is a specification.

This invention has for its object a table (of the kind called a flat top desk) possessing 10 a flexible cover contained in the interior of the desk, and which will completely cover the top of the same.

The annexed drawings show by way of example, the principle of this table, and one 15 form of its appliance.

Figure 1 is an elevation of the table.

Fig. 2 is a section on line 2—2.

Fig. 3 is a plan of the table.

Fig. 4 shows on the left side, the flexible 20 cover when it is completely open, and on the right the flexible cover when completely closed and the table covered.

Fig. 5 shows the grooves for the flexible 25 cover on the upwardly projecting sides of the table.

Fig. 6 shows the attachment of the upwardly projecting sides and their manner 30 of articulation.

The table proper is constructed with a 35 rectangular board A provided with hollow portion B for the purpose of receiving the flexible cover C. It is supported by posts and panels, so that it has all the advantages of an ordinary flat top desk. The table is provided with drawers D in its sides.

The flexible cover C is contained in the 40 central part E of the desk, and in no way interferes with the working of the drawers; also at each end of the table the panels turn down (Fig. 6) having a double object:

1. Enlarging the surface of the table when they are in the position shown by F¹ (Fig. 1) being maintained in this position by small slides H.

2. Forming the upwardly projecting ends 45 to receive the flexible cover when in the position shown in full lines.

To open or close the desk is a very simple operation. When it is desired to close it, the end pieces are placed in the position shown in full lines in Figs. 1 and 6; the making up piece G (Fig. 4, left side) is raised by the two finger holes I, the flexible cover is then pulled up by the piece G so that it occupies the closed position (Fig. 4, 55 right side).

This making up piece G is provided with a lock J which may be locked by a key K. In order to prevent the sides F from falling 60 down, the flexible cover C is provided on each leg with small projections L which fit into the molding M of the sides F.

With this design the same advantages are obtained with flat topped desk as with an 65 American roll top desk.

What I claim and desire to secure by Letters Patent of the United States is:—

A flat top desk having faces on opposite sides, a well arranged substantially midway between said faces, a flexible cover, arranged, when in open position, in said well, and end wall members hingedly connected to the ends of the desk and foldable thereagainst, said members, when extended above the top of the desk forming guides for said 70 flexible cover and coacting therewith to form a complete cover thereover, said members having grooves on their inner sides for the reception of the ends of the cover and also having guard molding on their inner 75 sides, said cover having projections to coact with said molding to lock the said members in upright position.

In witness whereof I affix my signature.

JEAN MARIE GLOPPE.
